INVENTOR.

UNITED STATES PATENT OFFICE.

WILLIAM W. BEVAN, OF MELROSE HIGHLANDS, MASSACHUSETTS.

DESIGN FOR A LACE-PAPER MAT.

40,708.

Specification for Design.

Patented May 24, 1910.

Application filed February 2, 1910. Serial No. 541,651. Term of patent 3½ years.

To all whom it may concern:

Be it known that I, WILLIAM W. BEVAN, a citizen of the United States, residing at No. 3 Richardson road, Melrose Highlands, in the county of Middlesex and State of Massachusetts, have invented a new, original, and ornamental Design for a Lace-Paper Mat, of which the following is a specification, reference being had to the accompanying drawing, forming part thereof.

The figure is a plan view of a lace paper mat, showing my new design.

I claim:

The ornamental design for a lace paper mat, as shown.

WILLIAM W. BEVAN.
